UNITED STATES PATENT OFFICE.

JOHN T. ALLMAND, OF DETROIT, MICHIGAN, ASSIGNOR TO FISHER CLOSED BODY COMPANY, OF DETROIT, MICHIGAN, A CORPORATION OF MICHIGAN.

WINDOW FOR VEHICLES.

1,107,189.

Specification of Letters Patent. Patented Aug. 11, 1914.

Application filed October 9, 1911. Serial No. 653,739.

To all whom it may concern:

Be it known that I, JOHN T. ALLMAND, a citizen of the United States, residing at Detroit, county of Wayne, State of Michigan, have invented a certain new and useful Improvement in Windows for Vehicles, and declare the following to be a full, clear, and exact description of the same, such as will enable others skilled in the art to which it pertains to make and use the same, reference being had to the accompanying drawings, which form a part of this specification.

My invention relates to windows for cars, automobiles and the like, and consists in certain improvements hereinafter described and specified in the claims.

In the drawings: Figure 1, is a vertical section of the window frame and slab of glass, showing the slab in the window well and showing in dotted lines how it is held in the window opening by the fence. Fig. 2, illustrates the means for holding and lifting the glass slab which constitutes the window. Fig. 3, is an illustrative portion of the rubber window way in which the glass slab slides.

In the drawings, similar letters refer to similar parts.

In the drawings, A, represents a sashless glass, preferably of plate glass of requisite thickness to insure sufficient strength. This window is not attached to or inclosed in a frame as usual, the only auxiliary feature consisting in a clip B attached to the upper edge by two screws b, b, and carrying a cross bar C projecting a sufficient distance from the face of the glass slab A to permit the cross bar to be grasped for the purpose of elevating or operating the window in the way.

D, is a rubber way taking the place of the ordinary window guide, being attached to the frame work in any appropriate or proper manner; this way has a cross section shown in the upper end at d and widens out at its lower end at d' sufficiently to permit the lower end of the glass slab to move laterally. This rubber grooved way D is fitted to a rubber sill E; this is attached horizontally to the upper edge of the frame work F at the top of and the side of the drop-recess or window-well and has an upward projecting strip that forms the fence over which the slab is lifted and which holds the slab in its uppermost position. Another way

of rubber lettered as G and shown in Fig. 3, is also attached to the wall or frame in the window well and has at its upper end a flaring groove g, which groove is continued by parallel edges g¹, g², down to the bottom 60 of the frame work. It will be seen from the showing in Fig. 1 and Fig. 3 that the strips g¹ and g² are comparatively thin and comparatively deep, so that a deep groove is formed and the rubber strips g¹ and g² are 65 capable of "clinging" to the glass so as to retard the descent of the slab when it is dropped. It will be seen that the groove g³ in this rubber piece G forms a continuation of the groove d² in the rubber piece D. The 70 frame work F incloses the drop-recess into which the slab A may be dropped out of the way.

In Fig. 1 the slab A is shown in the window well. When desired, the window is 75 raised by means of the hand bracket B into the position shown in dotted lines and is lifted over the fence e and the lower edge of it dropped down behind this fence, as shown in dotted lines in Fig. 1. It is obvious 80 and therefore needs no explanation that the opposite edge of the window has a frame work composed of exactly the same sort of material with the same sort of construction and arrangements except that it is reversed, 85 and therefore the window consisting of a single slab of glass A is held in position and capable of the operation as herein described.

My invention consists in dispensing entirely with the window sash and making the 90 window of a single slab of plate glass with an attachment for raising and lowering, and making the grooves in which it operates on the ways of the window of a resilient material which shall at once protect the glass 95 from breakage, destroy rattling and vibration and constitute a wind stop far superior to rigid materials ordinarily used for that purpose. I prefer to use rubber as this clings about the window and both excludes 100 the weather and prevents the too sudden drop of the slab into the drop-recess.

Having thus described my invention, what I desire to claim is:

1. The combination with a frame provided with a drop-recess or a window-well and a fence at the top of the well for holding the slab when it has been lifted out of the well, of rubber ways at the sides of the drop-recess or window-well and a slab of 110

glass having free edges, the said slab of glass being guided into the window-well by rubber ways that cushion it and retard its descent, substantially as described.

5. 2. The combination with a frame provided with a drop-recess or window-well and a fence for holding the slab after it has been lifted out of the well, of rubber ways at the sides of the drop-recess or window-well for 10 cushioning the glass and retarding its descent, a slab of glass having free edges and ways on the sides of the window frames above the well constructed of yieldable material adapted to cushion the glass and act 15 as a weather stop, substantially as described.

3. The combination with a frame provided with a drop-recess or window-well and a

fence at the top of the well for holding the slab when it has been lifted out of the well or rubber ways at the sides of the drop 20 recess or window-well, having comparatively thin and deep side strips that are capable of "clinging" to the glass and a slab of glass having free edges, the said slab of glass being guided into the window-well by 25 the rubber ways that cushion it and retard its descent, substantially as described.

In testimony whereof, I sign this specification in the presence of two witnesses,

JOHN T. ALLMAND.
